UNITED STATES PATENT OFFICE.

HENRY McDERMOTT, OF MILWAUKEE, WISCONSIN, ASSIGNOR TO McDERMOTT MECHANICAL CO., OF IRON RIVER, MICHIGAN, A CORPORATION OF MICHIGAN.

EXCAVATOR.

Application filed June 5, 1924. Serial No. 717,993.

To all whom it may concern:

Be it known that I, HENRY McDERMOTT, a citizen of the United States, residing at Milwaukee, in the county of Milwaukee and 5 State of Wisconsin, have invented certain new and useful Improvements in Excavators, of which the following is a specification, reference being had to the accompanying drawing, forming a part thereof.

10 This invention relates to an excavator.

It relates particularly to an excavator for use in mines to load the cars.

15 In accordance with the invention, as preferably embodied, an excavating bucket or scoop is mounted in a frame for rotation to pick up the ore or material and discharge it into a second bucket or loader arranged to empty its load into a mine car.

The buckets are mounted upon a single 20 frame or carriage and so arranged for cooperation together that the machine may be used in openings or tunnels of mines where the height of the drift would prohibit the use of excavators used heretofore, and necessitate removal of the ore by hand-shoveling.

25 An object of the invention is to provide an improved excavator of simple and compact construction.

30 Another object is to provide an improved excavator having an actuator for the bucket rotatably mounted in a frame or carriage, the bucket being directly secured to the actuator.

35 Another object is to provide an improved excavator having an excavating bucket and an actuator therefor, the actuator being adapted to receive the bucket on the return stroke so that it clears the muck.

40 Another object is to provide an improved excavator having excavating and unloading buckets mounted for cooperation together upon a single frame or carriage.

45 Another object is to provide an improved excavator having an actuator for the bucket rotatably mounted in a frame or carriage, the actuator working under fluid pressure.

Other objects and advantages will hereinafter appear.

50 For the purpose of illustrating the invention, an embodiment thereof is shown in the drawings, in which:

Figure 1 is a side elevation partly in section;

55 Fig. 2 is a plan view, partly in section;

Fig. 3 is a front end elevation;

Fig. 4 is a side elevation, showing the manner in which the excavating bucket cooperates with the loading bucket;

Figs. 5 and 6 are detail central sections 60 of the control valve for the actuator; and

Fig. 7 is a view, partly in section, looking toward the left in Fig. 4.

The invention comprises, in general, a frame or carriage 1, an excavating bucket 2, 65 and an actuator 3 for the bucket, the actuator being mounted to the frame for rotation with respect thereto.

The actuator 3 comprises a cylinder 4, heads 5, and a plate or cover 6. These parts 70 are assembled together for rotation on a shaft 7. The ends 8 of shaft 7 are reduced and fixed to the ends of members 9 of the frame by means of clamps 10 and bolts 11. The ends of members 9 are semi-cylindrical 75 to fit the reduced ends 8 of the shaft and to cooperate with the clamps 10 to hold the shaft against rotation with respect to the frame 1.

A plate or piston 12 is fixed to the shaft 80 7 and slidably fitted within cylinder 4 between the heads 5 thereof. The shaft 7 may be provided with a slot and the piston 12 inserted therein, as shown. The piston will thereby be fixed against rotation with 85 respect to the shaft. The excavating bucket 2 is pivoted directly to the actuator by means of lugs 13 on the cover 6 and lugs 14 on the bucket. A pin 15 passes through the lugs to form the pivotal connection. 90

The bucket 2 is provided with lugs or stops 16, arranged to engage the cylinder 4 to limit the movement of rotation of the bucket in one direction with respect to the cylinder, as shown in Fig. 1. 95

The forward edge of the bucket may be provided with suitable teeth 17 for breaking up the muck.

The reduced ends 8 of shaft 7 are provided with passages 18 and 19. 100

The passage 18 leads to the upper side of piston 12, as shown in Figures 1, 2 and 6, and is connected by a pipe 20 to the valve seat 21 of a valve 22.

The passage 19 leads to the under side of piston 12, and is connected by a pipe 23 to the valve seat 21, as shown. 105

The valve 22 is provided with a central passage 24 connected to an air supply by a pipe 25, and arranged to register with either 110

of the pipes 20 and 23 upon rotation of the valve by means of a suitable handle or lever 26.

The valve 22 is provided with a passage 27 arranged to connect pipe 20 with an exhaust passage 28 in the valve seat when the valve is moved to connect pipe 23 with the supply pipe 25 through the passage 24, as shown in Fig. 5. The upper side of the piston 12 will then be open to exhaust and the under side thereof placed under pressure to cause rotation of the actuator in a clockwise direction about the shaft 7, as viewed in Fig. 1.

A passage 29 in the valve is arranged to connect pipe 23 to an exhaust passage 30 when the valve is moved to connect pipe 20 with the supply pipe 25 through the passage 24, as shown in Fig. 6. The upper side of the piston 12 will then be placed under pressure and the lower side thereof open to exhaust to cause rotation of the actuator in a counter-clockwise direction until the stops 16 engage the cylinder 4.

The exhaust passage 30 may be restricted, as shown, to provide a cushion on the return stroke of the excavating bucket and prevent a too rapid rotation of the actuator back to its initial position.

A track or guide 31 is supported from the end of each arm 9 by means of a bracket 32 cast integrally therewith. The tracks 31 are arranged so that rollers 33 mounted at each side of the bucket 2 ride upon the tracks 35 to hold the bucket against rotation in a clockwise direction with respect to the actuator 3 until the bucket is in position over the unloading bucket. At this time the rollers 33 will leave the tracks and permit the bucket 2 to drop under the action of gravity to the position shown in Fig. 4, to discharge its load into the loading bucket.

A shaft 34, to which a sprocket wheel 35 and a pulley 36 are fixed, is mounted for rotation in brackets 37 cast integrally with the outer end of the frame 1. A chain 38 connects sprocket wheel 35 with a sprocket wheel 39 fixed in any suitable way to one of the heads 5 for rotation therewith, as shown in Fig. 2.

One end of a cable 40 is fixed to the pulley 36. The other end of the cable is secured to a bail 41 for the loading bucket 42. The cable 40 extends from under the pulley 36 so that when the actuator 3 and sprocket wheels 35 and 39 rotate in a clockwise direction, as viewed in Fig. 1, the cable 40 will unwind from the pulley 36.

The loading bucket 42 is provided with rollers or wheels 43 which ride upon tracks 44 fixed to the frame 1. When the cable 40 unwinds from pulley 36, the bucket 42 falls backwardly and rolls down the tracks 44 under the action of gravity. The length of the cable is such that when the excavating

bucket 2 is carried to its uppermost position by the actuator 3 and the rollers 33 are about to drop from the end of the tracks 31, the loading bucket 42 will be in position at the lower end of the tracks 44 to receive the load from the excavating bucket.

The loading bucket 42 is provided with hooks 45 at each side thereof to engage a cross member 46 of the frame 1 for the purpose hereinafter explained.

The frame 1 is pivotally mounted at 47 to a frame 48 provided with a curved track 49 and caterpillars 50. A worm wheel 51 and a roller 52 are fixed to a shaft 53 rotatably mounted in frame 1 in any suitable way, as shown in Fig. 1. A second shaft 54, provided with a worm 55 arranged to drive the worm wheel 51, is mounted in any suitable way to the frame 1. Hand wheels 56 are fixed to the ends of shaft 54 to rotate the shaft and cause the roller 52 to roll upon the track 49 and swing the frame 1 about the pivotal connection 47.

The actuator 3 and the excavating bucket 2 are thereby swung on the arc of a circle to work across the drift.

Rollers 57 may be mounted in the frame 1 at either side of roller 52 to engage the track 49 and hold the frame 1 against movement about shaft 53 as a center.

A plate 58, provided with teeth 59, may be pivoted at 60 to the frame 48 to hold the excavator against backward movement when the bucket 2 digs into the drift.

The caterpillars 50 may be driven by means of sprocket wheels 61 and 62 carried by frame 48 and connected by a chain 63. A gear wheel 64, fixed for rotation with gear wheel 62, may be driven by a gear wheel 65 rotated by a hand wheel 66, as shown in Fig. 1.

The frame 48 and caterpillars 50 are shown as a preferred means for mounting the frame 1, but of course any other suitable means may be used for this purpose.

A ballast box 67 is pivotally mounted at 68 in suitable brackets 69 secured to the rear end of frame 1. The box 67 may be filled with ore to act as ballast to equalize the tendency of the excavating bucket to pull the forward end of the frame downwardly when it digs into the drift.

The operation of the excavator is as follows:

The hand wheel 66 is rotated to move the caterpillars 50 and carry the excavator up to the drift.

Either hand wheel 56 may then be rotated to swing the frame 1 about the pivot 47 until the actuator 3 and excavating bucket 42 are in the desired position with respect to the drift.

Valve 22 is then moved to the position shown in Fig. 5 to place the under side of piston 12 under pressure and connect the

upper side thereof to the exhaust passage 28. The actuator 3 will then rotate in a clockwise direction, as viewed in Fig. 1, and carry the excavating bucket 2 into the drift.

5 At this time cable 40 will unwind from pulley 36, and the loading bucket 42 will roll down the tracks 44.

When the loading bucket reaches the end of the tracks 44, the rollers 33 on the excavating bucket will drop from the tracks 31, as explained above, to permit the excavating bucket to drop and discharge its load into the loading bucket, as shown in Fig. 4.

10 The valve 22 is then moved to shut off the pressure supply.

Movement of the valve to the position shown in Fig. 6 places the upper side of piston 12 under pressure and connects the under side thereof with the exhaust passage 30.

15 The actuator 3 will then rotate in a counter-clockwise direction and pull the bucket 2 out of the loading bucket 42. At this time, of course, the cable 40 is being wound upon pulley 36 and the loading bucket moving upwardly upon the tracks 44.

When the excavating bucket 2 clears the rear end of the loading bucket 42 it will drop by gravity into the V-shaped opening 30 in the actuator provided by the cover 6. The excavating bucket is thereby received by the actuator 3 on the return stroke so that it returns on a shorter radius, and clears the muck.

35 When the buckets reach their initial positions, as shown in Fig. 1, the valve 22 is moved to cut off the pressure supply.

The upper ends of the tracks 44 are curved upwardly, as shown in Fig. 1, so that the 40 forward rollers 43 will engage therewith before the cable 40 has been completely wound upon pulley 36. Continued rotation of pulley 36 will then cause the rear rollers of the loading bucket to leave the track and the bucket to rotate in a clockwise direction about the axis of the front rollers 43, until the hooks 45 engage the cross member 46. The loading bucket will then discharge its load into the mine car positioned below, as indicated by dotted lines in Fig. 1.

50 The parts are so designed that the pulley 36 will continue to rotate a slight amount so that the front rollers 43 will also leave the track, and the bucket will rotate a slight amount about the cross member 46 as a center. The loading bucket 42 will come to rest in the position shown in Fig. 1, with the front rollers 43 a slight distance above the tracks 44.

60 When the machine is started and the cable 40 unwound from pulley 36, the loading bucket 42 will drop until the front rollers thereof engage the tracks. This initial movement of the bucket will be relatively rapid so that the bucket will store up suffi-

cient moment of inertia to carry itself in a counter-clockwise direction about the front rollers 43 and insure engagement of the rear rollers 43 with the tracks.

65 The loading bucket will then roll down the tracks 44 under the action of gravity, as the cable 40 continues to be unwound from pulley 36.

The hooks 45 and the cross member 46 thereby provide simple means to insure the return movement of the loading bucket 42.

70 Automatic means may be provided to cooperate with the valve 22 to shut off the pressure supply when the buckets reach their extreme upper and lower positions.

75 The box 67 may be rotated with respect to the frame 1 to dump the ballast therefrom into the mine car to facilitate movement of the excavator from one position to another in the tunnel.

80 The piston 12 may be provided with slots at the edges thereof to receive steel strips 70 and springs 71 to press the strips outwardly against the inner surface of the cylinder 4. An air tight fit is thereby insured between the piston and the cylinder.

85 The reduced ends 8 of shaft 7 and the clamps 10 may be provided with registering keyways to receive keys 72. Additional means are thereby provided to prevent rotation of the shaft with respect to the frame 1.

90 The cover 6 for the cylinder 4 may be provided with reinforcing ribs 73.

95 Various changes of structure and arrangement of the parts may be adopted without departing from the spirit of the invention or the scope of the claims.

100 The invention claimed is:

1. In an excavator, in combination, a frame, an actuator rotatably mounted in said frame, a bucket pivotally connected directly to said actuator, and means to effect rotation of said actuator.

105 110 115 120 125 130

2. In an excavator, in combination, a frame, a shaft fixed to said frame, an actuator mounted for rotation on said shaft, said actuator comprising a cylinder and heads at either end thereof and a cover plate fixed thereto to fit said shaft, a piston slidably fitted within said cylinder between said heads, said piston being fixed to said shaft, a bucket pivotally connected to said actuator, and a valve arranged to effect a change in pressure between opposite sides of said piston to cause rotation of said actuator about said shaft.

3. In an excavator, in combination, a frame, an actuator mounted at one end thereof, an excavating bucket connected to said actuator, a loading bucket mounted for movement upon said frame, connection between said frame and said loading bucket to effect movement thereof with respect to said excavating bucket, said actuator and said connections being arranged for coopera-

tion together to move said buckets in a pre-determined manner so that the excavating bucket will discharge its load into the loading bucket when said excavating bucket is 5 at the end of its forward stroke, and means to effect movement of said actuator and said connections together.

4. In an excavator, in combination, a frame, a shaft fixed to said frame, a cylinder rotatably mounted on said shaft, a piston fixed to said shaft and slidably fitted within said cylinder, a valve, passages leading from said valve to either side of said piston, said valve being adapted to effect a 10 change of pressure between opposite sides of said piston to cause rotation of said cylinder about said shaft, and a bucket connected to said cylinder for movement therewith.

20 5. In an excavator, in combination, a frame, an actuator mounted at one end of said frame, an excavating bucket connected to said actuator for movement therewith, a loading bucket mounted upon said frame for reciprocatory movement with respect thereto, connections between said actuator and said loading bucket to move said buckets for co-operation together so that said excavating bucket discharges its load into said loading bucket when said buckets are substantially 25 at the ends of their forward strokes, said connections being arranged to return said buckets to their initial positions and to place said loading bucket in position to discharge its load, and means to effect movement of said connections.

6. In an excavator, in combination, a frame, a shaft fixed to said frame, a cylinder mounted for rotation on said shaft, a 40 piston fixed to said shaft and slidably fitted within said cylinder, a valve, passages leading from said valve to either side of said piston, said valve being adapted to effect a change of pressure between opposite sides 45 of said piston to cause rotation of said cylinder upon said shaft, an excavating bucket pivotally connected to said cylinder for movement therewith, a loading bucket mounted upon said frame for movement 50 with respect to said excavating bucket, connections between said actuator and said loading bucket to move said buckets for co-operation together so that said excavating bucket discharges its load into said loading bucket when said buckets are substantially 55 at the ends of their forward strokes, said connections being arranged to return said buckets to their initial positions and to place said loading bucket in position to discharge 60 said load, and means to effect movement of said connections.

7. In an excavator, in combination, a frame, an actuator rotatably mounted in said

frame, a bucket connected to said actuator for movement therewith, said actuator being arranged to move said bucket forwardly and return the same to its initial position, said actuator being recessed to receive said bucket on the return stroke thereof so that said bucket returns on a shorter radius.

8. In an excavator, in combination, a frame, a shaft mounted in said frame, a cylinder mounted upon said shaft for rotation with respect to said frame, and a bucket connected to said cylinder for movement therewith, said cylinder being arranged to carry said bucket forwardly and to return the same to its initial position, said cylinder being recessed to receive said bucket on the return stroke so that the bucket returns 80 on a shorter radius.

9. An excavator comprising a frame, a fluid-pressure motor carried thereby and having a cylinder supported for rotary movement upon operation of said motor, and a bucket connected to said motor for actuation thereby.

10. In an excavator of the character described, a frame, a motor supported by said frame and including a part mounted for rotary movement about an axis extending longitudinally thereof, a bucket, means connecting said bucket to said part for actuation thereby upon said movement of the same, and means for controlling the operation of said motor.

11. An excavator comprising a frame provided with tracks and means for supporting and positioning said frame with respect to the material to be worked, a loading bucket mounted on said tracks for forward and backward movement along the same, an excavating bucket associated with said frame and arranged for movement with respect thereto to discharge its load into said loading bucket when the latter is in one of its extreme positions, and actuating means common to said buckets for effecting said respective movements thereof.

12. An excavator comprising a frame provided with tracks and means for supporting and positioning said frame with respect to the material to be worked, a loading bucket mounted on said tracks for forward and backward movement along the same, an excavating bucket associated with said frame and arranged for movement with respect thereto to discharge its load into said loading bucket when the latter is in one of its extreme positions, and a fluid-pressure motor for effecting said respective movements of said buckets.

In witness whereof I have hereto affixed my signature.

HENRY McDERMOTT.
